DESIGN FOR A COMBINED FLOWER HOLDER AND STAND THEREFOR

Horace A. Fuld, New York, N. Y.

Application November 12, 1940, Serial No. 96,499

Term of patent 7 years

To all whom it may concern:

Be it known that I, Horace A. Fuld, a citizen of the United States of America, residing in New York city, county of New York, and State of New York, have invented a new, original, and ornamental Design for a Combined Flower Holder and Stand Therefor, of which the following is a specification, reference being had to the accompanying drawing, forming part thereof, wherein,

The characteristic feature of my design resides in the combination of the vertically split vase against the flat background, as shown.

I claim:

The ornamental design for a combined flower holder and stand therefor, substantially as shown and described.

HORACE A. FULD.
